ELECTRIC HYGROMETER

George Bouyoucos, East Lansing, Mich., assignor
to Michigan State Board of Agriculture, East
Lansing, Mich., a corporation of Michigan

Application April 10, 1943, Serial No. 482,564

8 Claims. (Cl. 201—76)

This invention relates to electrical apparatus for measuring the relative humidity of an atmosphere containing moisture, and more particularly to a novel form of moisture absorbing resistor for use therewith.

At the present time there are only three types of apparatus commonly employed for measuring relative humidity of air. They are the wet and dry bulb thermometers, the hair hygrometer, and apparatus for determining dew point. None of these devices is satisfactory, yet they have been in practically exclusive use for nearly a century because no superior apparatus has been produced.

The wet and dry bulb thermometers are inconvenient to use because they must be rapidly moved about in the atmosphere being measured. Furthermore, they are quite inaccurate at very high humidities and are entirely worthless for recording the lowest humidities.

The hair hygrometer type of apparatus is unsatisfactory because the hair employed repeatedly contracts and extends until in a short time it loses its elasticity and its calibration changes.

The dew point apparatus, on account of its complexities, is principally a laboratory apparatus. It is not suitable for general use.

Attempts have been made to overcome the disadvantages of the older types of apparatus by means of electrical hygrometers. These devices generally comprise a resistor that absorbs or adsorbs moisture and thereby changes in electrical conductivity. Theoretically the resistor absorbs moisture or gives it up to the atmosphere, and thereby decreases or increases in resistance, as the relative humidity of the atmosphere increases or decreases. Therefore, it is expected that by measuring the resistance of the resistor the relative humidity of the atmosphere can be determined.

Such electrical devices have not heretofore solved the problem because no satisfactory form of resistor has been available. The resistors heretofore employed have not been capable of quickly absorbing and giving up moisture directly in proportion to the moisture contained in the surrounding atmosphere and/or have not been of a sturdy enough construction to withstand prolonged usage and/or have deteriorated with use so as to require frequent replacement and/or have not been practical for outdoor use.

I have discovered that a resistor comprising a homogeneous mixture of plaster of Paris and glycerine is free from the above stated defects and is otherwise suitable for the very accurate measurement of relative humidity when used as

a part of an electric hygrometer. Accordingly, it is the principal object of this invention to provide a resistor for use with an electric hygrometer which comprises a substantially homogeneous mixture of plaster of Paris and a hygroscopic material such as glycerine.

Other objects and advantages of the invention will appear from the following description when read in connection with the accompanying drawings, wherein:

Figure 1 is a bottom plan view of a typical form of my improved resistor;

Figure 2 is a cross-sectional view taken on substantially the line 2—2 of Figure 1; and

Figure 3 is a cross-sectional view of a portion of an electrical hygrometer employing my invention.

The device illustrated in the drawing includes: a plate 10 of insulating material such as glass 20 or plastic, provided with a recess 11 on the lower face thereof, a pair of platinum wire loops 12 and 13 encircling the plate endwise and having portions thereof disposed within the recess; a thin layer of a mixture of plaster of Paris and glycerine disposed within the recess 11 of plate 10 and bridging the space between the loops of wire 12 and 13; a pair of electrical connectors 14 and 15 connected respectively to the platinum wire loops 12 and 13; and an inverted glass funnel or flask 16 enclosing the plate 10 and associated elements.

The electrical connectors 14 and 15 are adapted to be connected to any suitable electrical resistance measuring device such as a Wheatstone bridge or the like, which is not shown. Generally speaking, practical resistance measuring devices do not measure resistance with ease, at a range greater than 5,000,000 ohms. Therefore, it is desirable to design and proportion the resistor so as to provide for a range of resistances which will not exceed that figure.

The essence of the present invention resides in the mixture of plaster of Paris and glycerine which constitutes the resistor per se. The proportions of these materials which are to be used will depend upon the use to which the instrument is to be put. For example, if a relatively large proportion of glycerine is used the resistance is decreased. If a relatively small proportion of glycerine is used the resistance is increased.

In view of the foregoing, it will be understood that the present invention lends itself to many different specific embodiments. Accordingly, the details of only one specific operative embodiment are herein shown and described. Of course, the

invention is not limited to that particular embodiment.

The plate 10 is a plastic such as "Lucite" or "Styron." It is $\frac{3}{4}$ inch wide, 1 inch long, and $\frac{1}{8}$ inch thick. In one face of the plate and extending longitudinally thereof is a groove or trench 11. The trench 11 has a flat bottom and vertical parallel side walls. The trench is $\frac{1}{8}$ inch wide and $\frac{1}{16}$ inch deep and extends throughout the length of the plate 10.

Two platinum wires 12 and 13 of No. 28 gauge are extended completely around the glass plate and the ends of each are soldered together to hold them in place. The wires lie in the trench 11 in spaced parallel relation to each other and contact the sides of the trench. The platinum wires 12 and 13 are connected to insulated wire leads 14 and 15 respectively. Lead 14 is connected to wire 12 at one end of the plate 10, while lead 15 is connected to wire 13 at the other end of the plate, so that the resistor may be suspended within a suitable housing. The leads 14 and 15 extend away from the grooved face of the plate 10 so that when arranged as shown in Figure 3 the grooved face is downward.

After the wires 12, 13, 14 and 15 have been applied and properly insulated, the grooved face of the glass plate 10 is held face up and a small quantity of freshly made substantially homogeneous mixture of plaster of Paris and a water solution of glycerine is poured into the trench. The mixture comprises 10 grams of chemically pure plaster of Paris and 10 cubic centimeters of a 15% glycerine solution. Just enough of the mixture to cover the wires 12 and 13 is poured into the trench 11 and is spread in a thin layer therein so as to bridge the space between the wires. The quantity needed will be less than $\frac{1}{16}$ c. c. The mixture is permitted to set, which takes about 5 minutes, and is then cured by heating for several hours in an oven at approximately 130° F. This results in a very hard but porous solid 17. It has been found that plaster of Paris sets harder in a glycerine-water solution than in plain water. Thus, the resistor is tough, rugged and durable.

The mixture of plaster of Paris and glycerine has the power of absorbing moisture from the surrounding atmosphere or of giving it up to the atmosphere so that the moisture in the mixture is always in equilibrium with the moisture in the atmosphere. The electrical resistance of the mixture will vary as the moisture content of the surrounding atmosphere varies.

In the case of the resistor having the proportions described above and at a temperature of 70° F., the resistance varies from about 2,000 ohms at 100% to approximately 4,000,000 ohms at 10% relative humidity. To measure the relative humidity of the atmosphere, the resistance of the mixture is measured by causing a current to flow across the mixture between the platinum wires 12 and 13 and measuring the resistance of the mixture. In this manner, the relative humidity can be accurately determined, even at temperatures below 32° and above 100° F.

The resistor may be calibrated by subjecting it to various known vapor saturations created in stirred air in a closed space by distilled water or super saturated solutions of such salts as lithium chloride, magnesium chloride, magnesium nitrate, sodium chloride and potassium nitrate, at definite temperatures. The resistor may be calibrated also against a wet and dry bulb thermometer or a dew point measuring ap-

paratus. As the electrical resistance is affected by temperature, proper correction is made in accordance with the existing temperature. This can be done by preparing suitable tables from test data obtained by noting resistance at constant humidities and variable temperatures.

In order to protect the resistor against rain, snow, wind, dust and water condensation, it is inserted into the inverted glass funnel or flask 16, as shown in Figure 3. The grooved face of the glass plate 10 faces downward and the leads 14 and 15 are brought out through the neck of the funnel. The open end of the funnel is plugged to prevent the entrance of rain, snow and dust. The funnel may be suspended in inverted position by any suitable means.

The invention has proven extremely dependable, practical and serviceable. It is highly sensitive and accurate. It will function in all ordinary conditions, and can be employed under extraordinary conditions, such as extremely high temperatures and low humidities.

The invention can be placed in the inverted funnel and kept outdoors in shelters such as those used by the U. S. Weather Bureau for housing recording instruments, and its accuracy will not be impaired, even at extremely low temperatures. Its calibration is permanent.

As indicated hereinbefore, the practical range of operation of the device can be varied by varying the proportion of glycerine in the mixture. For example, if it is desired to measure extremely low humidities, the proportion of glycerine may be increased.

Likewise, the width of the trench and the consequent spacing of the wires 12 and 13 may be varied as another way of changing the resistance to change the range of operation or to meet extraordinary conditions.

From the foregoing, it will be apparent that the present invention provides a resistor which is extremely sensitive and accurate—the range of measurement being from 4,000,000 ohms at 10% relative humidity to 2,000 ohms at 100% relative humidity, according to one embodiment. In all embodiments, resistor will be durable and of a permanent nature due to its composition. Likewise, I have discovered that this particular composition has the capacity to correctly reflect the humidity condition of the surrounding atmosphere.

The scope of the invention is indicated in the appended claims.

I claim:

55. 1. An electrical resistance element comprising a thin layer of a homogeneous mixture of plaster of Paris and glycerine.
56. 2. An electrical resistance element comprising a homogeneous mixture of plaster of Paris and a hygroscopic polyhydric alcohol.
57. 3. An electrical resistance element comprising a solid resulting from the mixture of equal parts of plaster of Paris and a solution of a hygroscopic polyhydric alcohol and water.
58. 4. An electrical resistance element comprising a solid resulting from the mixture of equal parts of plaster of Paris and a 15% glycerine solution in water.
59. 5. An electrical resistance element comprising a non-conducting base, a thin layer of a homogeneous mixture of plaster of Paris and a hygroscopic polyhydric alcohol thereon, and a pair of spaced apart electrical conductors in conductive relation with said layer.
60. 6. An electrical resistance element comprising

a non-conducting base having a shallow trench in one face thereof, a pair of spaced apart parallel electrical conductors in said trench, and a thin layer of a homogeneous mixture of plaster of Paris and a hygroscopic polyhydric alcohol in said trench, said mixture being in electrical contact with both of said conductors.

7. An electrical resistor comprising a flat strip of insulating material having a channel shaped trench in one face thereof, a pair of spaced apart parallel conductors in said trench, and a thin layer of a homogeneous mixture of plaster of

Paris and glycerine in said trench, said mixture being in contact with both of said conductors.

8. An electrical resistance element comprising a non-conducting base having a shallow trench in one face thereof, a pair of spaced apart parallel electrical conductors in said trench, and a thin layer of a homogeneous mixture of plaster of Paris and a hygroscopic polyhydric alcohol in said trench, said mixture being in electrical contact with both of said conductors.

GEORGE BOYOUCOS.
